PSYCHROMETRICALLY CONTROLLED AIR CONDITIONING SYSTEM

James C. Marlow, Atlanta, Ga., assignor to B. F. Sturtevant Company, Boston, Mass.

Application June 23, 1942, Serial No. 448,074

9 Claims. (Cl. 257—3)

This invention relates to the conditioning of air and relates more particularly to air conditioning systems and to automatic controls therefor for maintaining desired relative humidities and dry bulb temperatures in the conditioned space.

In the processing of many materials in manufacturing, it is important to maintain a substantially constant relative humidity and a substantially constant dry bulb temperature in the conditioned space at any predetermined setting of the control instruments. In so far as is known in all prior systems while it was possible to maintain the relative humidity and dry bulb temperature within limits which had to be accepted as tolerant, the fluctuations were substantial and undesired.

Objects of this invention are to maintain a substantially constant relative humidity and a substantially constant dry bulb temperature in the air in an air conditioned space.

The invention will now be described with reference to the drawing which illustrates diagrammatically an air conditioning system embodying this invention.

The centrifugal fan 5 driven by the electric motor 6 draws in fresh outdoor air through the inlet 7. The fresh air passes in the order named, through the preheater 8, between the dampers 9, through the plenum chamber 10, the filters 11, the sprays from the air washer nozzles 12, between the finned tubes of the evaporator 13, through the reheater 14, between the face dampers 15 when they are open, into the plenum chamber 16, and then into the inlet of the fan 5. The conditioned air is discharged through the duct 17 into the conditioned space 18.

Air recirculated from the space 18 is drawn by the suction of the fan 5 through the duct 19, and when the by-pass dampers 20 in the by-pass duct 21 are open, a portion of the recirculated air passes as by-pass air into the plenum chamber 16 for mixture with the chilled, dehumidified air from the evaporator 13.

Another portion of the recirculated air from the duct 19 is drawn into the plenum chamber 10 and passes with the recirculated air through the above described apparatus located between the plenum chamber 10 and the space 18.

As is well known the by-pass air serves to reheat the chilled air for tempering purposes, and a saving in refrigeration is affected by recirculating air from the space served, through the conditioner since the condition of the recirculated air is usually nearer the desired condition than the outdoor air.

The evaporator 13 may be of well known construction consisting of a plurality of relatively closely spaced horizontal tubes provided with extended surface fins, with interconnected return bends and inlet and outlet headers. Any suitable volatile refrigerant such as "Freon" is supplied from the compressor-condenser 22 through the pipe 23 and is returned through the suction pipe 24 and the suction valve 25.

Steam from the source 26 is supplied through the pipe 27 and the valve 28 to the preheater 8 and through the pipe 29 and valve 30 to the reheater 14.

The pump 31 circulates spray water from the sump (not illustrated) under the spray nozzles and evaporator 13, through the valve 38, the pipe 39 and the nozzles 12. The water from the nozzles 12 preferably sprays upon the evaporator. As is usual a float controlled make-up water supply may be used.

The dry bulb thermostat 31 and the hygostat 32 control the operation of the system, through compressed air from the source 33 supplied to these control instruments through the tube 34.

25 The dash-dot lines indicate air tubes connecting the control instruments and the diaphragm type motors controlled by them.

The motor 35 is actuated by the hygostat 32 to adjust the steam valve 28 which is normally closed. The motor 35 is biased to operate to open the valve 28 at an air pressure between ten and fourteen pounds.

The motor 36 is actuated by the thermostat 31 to adjust the steam valve 30 which is normally closed. The motor 36 is biased to operate to open the valve 30 at an air pressure between nine and thirteen pounds.

The motor 40 is actuated by the hygostat 32 to adjust the valve 38 for controlling the volume of water sprayed by the nozzles 12. The valve 38 is normally closed. The motor 40 is biased to open the valve 38 at an air pressure between seven and eleven pounds.

45 The motor 50 is actuated by the hygostat 32 to adjust the refrigerant suction valve 25 which is normally open. The motor 50 is biased to close the valve 25 at an air pressure between four and eight pounds. The air from the hygostat 32 to the motor 50 passes through the valve 41 which is normally open. It is controlled by the diaphragm type motor 42 which in turn is controlled by the thermostat 31 which acts as will be described to prevent the hygostat from closing the suction valve 25 until the air in the con-

ditioned space has dropped to its predetermined temperature.

The motor 43 is actuated by the thermostat 31 to adjust the by-pass dampers 20 which are normally closed. The motor 43 is biased to open the dampers 20 at an air pressure between four and nine pounds.

The motor 44 is actuated by the thermostat 31 to adjust the face dampers 15 which are normally open. The motor 44 is biased to close the dampers 15 at an air pressure between four and nine pounds.

The solenoid 45 is connected to the electric circuit of the motor 6 so that when the switch 46 is opened for disconnecting the motor 6 from the electric source 47, the solenoid 45 is de-energized and closes the valve 48 in the air tube 34 connecting the air source 33 with the control instruments. This causes the motor 49 to close the normally open fresh air dampers 8.

The hygrostat 32 is of the reverse acting type designed to pass air to the motors it controls on a falling relative humidity. If the relative humidity in the conditioned space 18 starts to fall below the desired condition which, for example, may be 65%, the hygrostat will start gradually to pass air to the various motors it actuates. When the air pressure released by the hygrostat reaches four pounds, the refrigerant suction valve 25 will be gradually closed by the motor 50 and when the air pressure reaches eight pounds, the valve 25 will be fully closed thus completely shutting off the refrigeration. If this is not sufficient to raise the relative humidity in the space 18, the hygrostat will continue to pass air and at seven pounds pressure the spray control valve 38 will begin to be opened by the motor 40 and when the air pressure reaches eleven pounds the sprays will be full on tending to increase the relative humidity of the air. If in spite of this, the desired relative humidity is not restored, the air pressure will continue to build up and at ten pounds pressure, the pre-heater steam valve 28 will start to be opened by the motor 35 and when the air pressure reaches fourteen pounds, the valve 28 will be fully open. This causes maximum heat through the pre-heater which results in an increase in the dew point temperature of the air leaving the spray from the nozzles 12.

Instead of using the air preheater 8 as described for raising the relative humidity of the air, a water heater supplied with steam from the source 26 could be used for heating the water supplied to the spray nozzles 12.

Instead of having the valve 25 completely closed as described, it may be desirable to have the valve stop adjusted so that the valve may be almost but not completely closed. This will prevent the usual low pressure control from shutting down the compressor, if a local, individual compressor is used, and will result in the compressor being in condition for immediate action when the hygrostat or thermostat calls for refrigeration.

It is to be noted that the operating pressures for the various motors have been overlapped so that each proportioning motor will be in immediate reserve and ready to perform without delay upon demand from the hygrostat.

The dry bulb thermostat 31 is also of the reverse acting type designed to pass air to the motors it controls, upon a falling temperature. When the dry bulb temperature in the conditioned space 18 starts to fall below the control

temperature which, for example, may be 70° F., the thermostat will start to pass air and when the air pressure has reached four pounds, the face dampers 15 will start to be closed by the motor 44 and the bypass dampers 20 will start to be opened by the motor 43. When the air pressure has reached nine pounds the face dampers 15 will be fully closed. If this does not raise the dry bulb temperature, the thermostat will continue to pass air and when the air pressure reaches nine pounds, the reheat steam valve 30 will start to be opened by the motor 36 and when the air pressure reaches thirteen pounds, the valve 30 will be fully open.

15 The valve 41 in the air line from the hygrostat 32 to the motor 50 controlling the refrigerant suction valve 25, is controlled by the thermostat 31 so that the valve 41 is closed preventing the hygrostat from supplying air to close the suction valve 25 when the temperature in the space 18 is above its predetermined setting. When this condition occurs and the relative humidity is too low, the operation of the preheater and the sprays as described has been found sufficient to 25 restore the relative humidity to its predetermined point.

In a typical installation embodying this invention the dry bulb temperatures and the relative humidities in the conditioned space were recorded on a standard clock driven recording chart and the fluctuations in the lines drawn were barely perceptible to the eye showing that the desired conditions were maintained substantially constant for all practical purposes.

35 While the controls have been illustrated and described as being of the air actuated type, electric or other equivalent controls could, of course, be used.

While one embodiment of the invention has 40 been disclosed for the purpose of illustration, it should be understood that the invention is not limited to the exact apparatus and arrangement of apparatus illustrated, as modifications thereof may be suggested by those skilled in the art 45 without departure from the essence of the invention.

What is claimed is:

1. An air conditioning system comprising an air heater, an air washer, an air cooling refrigerant evaporator, and including means for moving air to be conditioned through said heater, said washer and said evaporator and for supplying it into the space to be conditioned, a heating fluid source connected to said heater, a water source connected to said washer, a refrigerant source connected to said evaporator, and means including means responsive to changes in the relative humidity in said space for first decreasing the supply of refrigerant from said refrigerant source to said evaporator, for next initiating the supply of water from said water source to said washer, and for next initiating the supply of fluid from said heating source to said heater, upon a fall in relative humidity in said space below the desired level.

2. An air conditioning system comprising an air heater, an air washer, an air cooling refrigerant evaporator, and including means for moving air to be conditioned through said heater, said washer and said evaporator and for supplying it into the space to be conditioned, a heating fluid source connected to said heater, a water source connected to said washer, a refrigerant source connected to said evaporator, and means including means responsive to changes in the

responsive to temperature changes in said space for first decreasing the supply of refrigerant from said refrigerant source to said evaporator from a maximum to a minimum upon a fall in the relative humidity in said space below the desired level, for then if the relative humidity is not restored, initiating the supply of water from said water source to said washer and regulating it from a minimum to a maximum, and then if the relative humidity is not restored, for initiating the supply of fluid from said heating source and regulating it from a minimum to a maximum.

3. An air conditioning system comprising an air heater, an air washer, an air cooling refrigerant evaporator, and including means for moving air to be conditioned through said heater, said washer and said evaporator and for supplying it into the space to be conditioned, a heating fluid source connected to said heater, a water source connected to said washer, a refrigerant source connected to said evaporator, and means including means responsive to changes in the relative humidity in said space for first decreasing the supply of refrigerant from said refrigerant source to said evaporator from a maximum to a minimum upon a fall in the relative humidity in said space below the desired level, for then if the relative humidity is not restored, initiating the supply of water from said water source to said washer and regulating it from a minimum to a maximum, and then if the relative humidity is not restored, for initiating the supply of fluid from said heating source and regulating it from a minimum to a maximum, the regulation of said evaporator, said washer and said heater being overlapped whereby the supply of water to said washer is initiated before the supply of refrigerant to said evaporator has been reduced to a minimum, and the supply of heating fluid to said heater being initiated before the supply of water to said washer has been increased to a maximum.

4. An air conditioning system comprising an air cooling refrigerant evaporator, an air heater on the downstream side of said evaporator, face dampers for bypassing air from said evaporator around said heater, a duct conducting air from the conditioned space as bypass air to the downstream side of said heater, a duct damper in said duct, said system including means for moving air through said evaporator and heater and for supplying it into the space to be conditioned and for moving air from said space through said duct, and means including a thermostat responsive to temperature changes in said space for first decreasing the supply of refrigerant to said evaporator, for next adjusting said face dampers towards closed position and adjusting said duct damper towards open position, and for next admitting a heating medium into said heater upon a fall in the temperature in said space below the desired level.

5. An air conditioning system comprising an air cooling refrigerant evaporator, an air heater on the downstream side of said evaporator, face dampers for bypassing air from said evaporator around said heater, a duct conducting air from the conditioned space as bypass air to the downstream side of said heater, a duct damper in said duct, said system including means for moving air through said evaporator and heater and for supplying it into the space to be conditioned, and for moving air from said space through said duct, and means including a thermostat re-

sponsive to temperature changes in said space for first adjusting the supply of refrigerant to said evaporator upon a fall in the temperature in said space below the desired level, from a maximum to a minimum, then if the temperature is not restored, for adjusting said face dampers from a maximum open to a minimum open position and for adjusting said duct damper from a minimum open to a maximum open position, and then if the temperature is not restored, for initiating the supply of heating fluid to said heater and adjusting same from a minimum to a maximum until the temperature is restored.

6. An air conditioning system comprising an air cooling refrigerant evaporator, an air heater on the downstream side of said evaporator, face dampers for bypassing air from said evaporator around said heater, a duct conducting air from the conditioned space as bypass air to the downstream side of said heater, a duct damper in said duct, said system including means for moving air through said evaporator and heater and for supplying it into the space to be conditioned, and for moving air from said space through said duct, and means including a thermostat responsive to temperature changes in said space for first adjusting the supply of refrigerant to said evaporator upon a fall in the temperature in said space below the desired level, from a maximum to a minimum, then if the temperature is not restored, for adjusting said face dampers from a maximum open to a minimum open position and for adjusting said duct damper from a minimum open to a maximum open position, and then if the temperature is not restored, for initiating the supply of heating fluid to said heater and adjusting same from a minimum to a maximum until the temperature is restored.

7. An air conditioning system comprising a humidifier, an air cooler, an air heater at the downstream side of said cooler, face dampers for bypassing air from said cooler around said heater, a duct for conducting air from the conditioned space as bypass air to the downstream side of said heater, a damper in said duct, said system including means for moving air through said humidifier, cooler and heater and supplying it into said space and for moving air from said space through said duct, means including means responsive to changes in the relative humidity in said space for first decreasing the effectiveness of said cooler, upon a fall in the relative humidity in said space, from a maximum to a minimum, and then if the relative humidity is not restored, initiating the action of said humidifier and then increasing its effectiveness from a minimum to a maximum, and means including a thermostat responsive to temperature changes in said space for first adjusting the supply of cooling medium to said cooler upon a fall in the temperature in said space below the desired level, from a maximum to a minimum, and then if the temperature is not restored for adjusting said damper from minimum open position to maximum open position and for adjusting said face dampers from maximum

open position to minimum open position, and then if the temperature is not restored for actuating said heater and for increasing its effectiveness from a minimum to a maximum.

8. An air conditioning system comprising a humidifier, an air cooling refrigerant evaporator, an air heater at the downstream side of said evaporator, face dampers for bypassing air from said evaporator around said heater, a duct for conducting air from the conditioned space as bypass air to the downstream side of said heater, a damper in said duct, said system including means for moving air through said humidifier, evaporator and heater and supplying it into said space and for moving air from said space through said duct, means including means responsive to changes in the relative humidity in said space for first adjusting the supply of refrigerant to said evaporator, upon a fall in the relative humidity in said space, from a maximum to a minimum, and then if the relative humidity is not restored, initiating the action of said humidifier and then increasing its effectiveness from a minimum to a maximum, means including a thermostat responsive to temperature changes in said space for first adjusting the supply of refrigerant to said evaporator upon a fall in the temperature in said space below the desired level, from a maximum to a minimum, and then if the temperature is not restored for adjusting said damper from a minimum open position to maximum open position and for adjusting said face dampers from maxi-

mum open position to minimum open position, and then if the temperature is not restored for actuating said heater and for increasing its effectiveness from a minimum to a maximum, and means controlled by said thermostat for preventing said humidity responsive means from decreasing the supply of refrigerant to said evaporator when the temperature in said space is above the desired level.

9. An air conditioning system comprising a humidifier, an air cooler, air reheating means, said system including means for moving air through said humidifier, said cooler and said reheating means and for supplying it into the conditioned space, means including means responsive to changes in the relative humidity in said space for first adjusting the effectiveness of said cooler towards minimum upon a decrease in the relative humidity in said space below the desired level and then if the humidity is not restored, for actuating said humidifier, means including a thermostat responsive to temperature changes in said space for first adjusting the effectiveness of said cooler towards minimum, upon a fall in the temperature in said space below the desired level, and then if the temperature is not restored, for initiating the action of said reheating means, and means controlled by said thermostat for preventing said humidity responsive means from decreasing the effectiveness of said cooler when the temperature in said space is above the desired level.

JAMES C. MARLOW.
